(57) CLAIM

The ornamental design for a saddle bag ornament, as shown and described.

DESCRIPTION

FIG. 1 is a side elevational view of a saddle bag ornament, illustrating my new design of the present invention;

FIG. 2 is an end elevational view thereof, from the right end as viewed in FIG. 1;

FIG. 3 is an opposite end elevational view, taken from the left end of FIG. 1;

FIG. 4 is a top plan view thereof;

FIG. 5 is a bottom plan view thereof; and,

FIG. 6 is a rear elevational view thereof.
